DESIGN FOR A COAT

Samuel H. Dick, Brooklyn, N. Y.

Application June 10, 1941, Serial No. 101,367

Term of patent 3½ years

To all whom it may concern:

Be it known that I, Samuel H. Dick, a citizen of the United States, residing in Brooklyn, New York city, in the county of Kings and State of New York, have invented a new, original, and ornamental Design for a Coat, of which the following is a specification, reference being had to the accompanying drawing, forming part thereof.

Fig. 3 is a front view of the coat shown in Fig. 1, with the outer panels turned back illustrating the inner panel and button closure means.

I claim:

The ornamental design for a coat, substantially as shown.

SAMUEL H. DICK.
